UNITED STATES PATENT OFFICE.

JAMES F. ROWLEY, OF DES MOINES, IOWA.

ARTIFICIAL LEG.

SPECIFICATION forming part of Letters Patent No. 314,726, dated March 31, 1885.

Application filed January 10, 1885. (No model.)

To all whom it may concern:

Be it known that I, JAMES F. ROWLEY, a citizen of the United States of America, and a resident of the city of Des Moines, in the county 5 of Polk and State of Iowa, have invented an Improved Artificial Leg, of which the following is a specification.

My object is, first, to provide a lateral motion for the foot at the ankle-joint as well as forward and backward motions; second, to make the leg extensible and adjustable to correspond with the growth of a natural leg that may be developing on a growing person at the side of an artificial leg; third, to produce a strong and 15 elastic joint in the front of the foot that will be self-adjusting under pressure.

I accomplish the results contemplated, as hereinafter fully set forth, and pointed out in the claims, and illustrated in the accompanying drawings, in which—

Figure 1 is a vertical and longitudinal section of my invention; Fig. 2, a view of the top portion of the leg, taken at right angles relative to Fig. 1, to show my device for lengthening the leg. Fig. 3 is a transverse section of the top section and extensible devices, and Fig. 4 a bottom view of the foot.

A represents the bulk of the foot, made of wood.

30 B is a recess formed in the central portion of its under side.

C is a concavo-convex solid plate, made of hard rubber or metal, fitted in a concave formed in the top of the foot and firmly secured thereto by means of screws.

D is the lower portion and shank of the leg, made of wood and cut off square at both ends and connected with the foot by means of a ball-and-socket joint. A vertical bore is provided 40 in the center of its lower end to form a socket for a ball.

f is a ball on the end of a screw-bolt secured in the socket by means of a solid rubber or metal base-piece, g, that is fixed against the 45 square bottom of the shank and that has a boss, g', on its upper side and center extending into the socket and against the ball f, as clearly shown in Fig. 1. The under side of the base-piece g is convex, and fits in the concave top 50 of the plate C, that is fixed to the foot.

h is a tubular elastic rubber block fitted in a bore or chamber formed in the under side and center of the base-piece g.

i is a clamping-bolt formed integral with or fixed to the ball f and extending through the 55 base-piece g, the boss g', the elastic block h, and thence through a bore into the recess B in the bottom of the foot. By simply drawing a nut on the screw-threaded end of the clamping-bolt the leg and the foot are firmly joined 60 together in such a manner as to produce an ankle-joint that will allow flexion in every direction.

k represents an elastic tendon fixed to the front portion and lower end of the leg D, and 65 its lower portion divided and extended on the opposite sides of the foot into the recess B, and there fastened to restrict the rearward flexion of the leg relative to the foot and to aid in keeping the foot in a natural position.

L represents a tubular top end of the leg, extending from the wooden shank D to the knee-joint.

m m represent the lower ends of metal bars that are provided with joints in their centers 75 to produce a knee-joint in a common way. Their top ends are rigidly fixed to a socket adapted to receive the stump of a natural leg, and their lower ends are fixed to a collar, n, that forms part of the lower end of the tubular 80 top L.

r r represent metal bearings fixed in the opposite sides of the wooden shank D. They correspond in shape with the lower ends of the bars m, that are designed to slide up and down 85 in the bearings and to be fastened at any point desired by means of set-screws passed through perforations in the collar n, bars m, and bearings r. By forming a series of perforations or screw-seats in each bearing r the set-screws 90 can be readily changed from one point to another, as required, to adjust the tubular top L relative to the solid shank D for the purpose of lengthening or shortening the complete leg.

s represents the front end or toes of the foot. 95 Its rear convex end is fitted to the front end of the foot and hinged thereto by means of a metal rod, s', that has an eye at one end and a screw on the opposite end, as clearly shown in Fig. 1.

s" represents an elastic pad fixed flat against the bottom of the foot and toes to restrict the flexion of the hinged toes, to perform the function of the natural ball of a foot, and to retain 5 the toe in straight and normal position relative to the foot; also, to draw it down when the pressure is relaxed that has inclined it upward.

From the foregoing description of the construction and function of each element and sub-10 combination, the unitary offices of all the parts and the practical operation and utility of my complete invention will be obvious to persons familiar with artificial limbs.

I am aware that the upper portion of the leg 15 has been adjustably connected with the foot, so that the leg could be lengthened below the knee-joint by means of a screw-threaded rod in the center; but my manner of combining the tubular top portion with a solid shank by 20 means of bars fixed to the opposite sides of the tubular part and bearings fixed to the solid shank is new and greatly advantageous.

I am also aware that ankle-joints have been made to allow lateral motion; but my manner 25 of shaping and connecting an elastic block and elastic tendons with the wooden and metallic parts, to provide flexion in every direction without relaxing the tension of the joint, is novel and greatly advantageous.

30 I claim as my invention—

1. In an artificial leg, the combination of a wooden foot having a recess in its bottom and a solid rigid plate having a concave top surface fixed on the top of the foot, a wooden leg or shank having a central vertical bore in its 35 bottom, a solid rigid base-piece having a convex surface on its under side and a boss on its top fixed to the bottom of the wooden shank, and a ball having a screw-bolt extending from within the bore of the shank into the recess in 40 the bottom of the foot, to operate in the manner set forth.

2. An elastic plug, *h*, in combination with the base-piece *g g'*, and the ball *f*, having a fixed rod or bolt, *i*, as and for the purposes 45 stated.

3. An elastic tendon, *k*, split at its lower end, in combination with the shank of a leg and a foot hinged to the shank, as and for the purposes specified. 50

4. The combination of the tubular top end of an artificial leg having fixed jointed bars *m* with the shank of a leg having fixed bearings *r*, to operate in the manner set forth, for the purposes stated.

JAMES F. ROWLEY.
